UNITED STATES PATENT OFFICE.

WALTER SCOTT, OF CHICAGO, ILLINOIS.

SHEET-DELIVERY APPARATUS FOR PRINTING-MACHINES.

SPECIFICATION forming part of Letters Patent No. 228,782, dated June 15, 1880.

Application filed October 24, 1879.

To all whom it may concern:

Be it known that I, WALTER SCOTT, of Chicago, in the county of Cook and State of Illinois, have invented certain new and useful 5 Improvements in Sheet-Delivery Apparatus for Printing-Machines, which are fully described in the following specification, reference being had to the accompanying drawings, in which—

10 Figure 1 represents a plan view of a machine embodying my improvements; Fig. 2, a longitudinal vertical section of the same, taken on the line *x x*, Fig. 1; Fig. 3, a detail view, on an enlarged scale, of a portion of the trans-
ferring griper-cylinder; Fig. 4, a transverse section of the same; Fig. 5, a side elevation of one of the folding-cylinders; Fig. 6, a side elevation of the machine, taken on the back side thereof; Fig. 7, a transverse section taken 15 on the line *y y*, Fig. 1; and Fig. 8, a detail transverse section taken on the line *z z*, Fig. 6.

My invention relates to machines in which a web of paper is printed and the printed sheets severed and delivered automatically to 20 folding mechanism, by which they are folded the required number of times and delivered in folded form.

The invention consists in special devices whereby two or more sheets may be gathered 25 upon a cylinder and then transferred in a pack to the folding mechanism.

It also consists in various special devices and combinations of devices for delivering and folding the sheets, all of which will be 30 hereinafter more fully described, and pointed out more definitely in the claims.

In the drawings, A represents the supporting-frame in which the various cylinders and other parts of the machine are mounted, and 35 B the last set of impression-cylinders of the printing-machine. In rear of these impression-cylinders are cutting-cylinders B' B', for severing or perforating the printed web, thereby dividing it into sheets, one of the cylinders 40 being provided with a cutting or perforating knife, *b*, and the other with a cutting-groove, *b'*.

A hollow cylinder, C, is mounted in the frame somewhat in rear of the cutting-cylinders, and is provided with ordinary transfer-ring-grippers *c*. An air-blast pipe, C', running up at the back side of the machine, enters the head of the cylinder, and is extended along

through it in the interior thereof to the opposite end, and is provided with a series of small branches, *c'*, leading from the main pipe 55 in the interior of the cylinder to the shell of the latter, where they communicate with a series of perforations, *c''*, running lengthwise of the cylinder about on a line with the nip of its grippers. 60

A cylinder, D, is arranged a little below and in the rear of the cylinder C, with which it runs nearly in contact. This cylinder is plain surfaced, and is provided with a series of openings, *d*, to accommodate the grippers *c* 65 in the cylinder C.

Just in rear of the cutting-cylinders is a pair of ordinary tape-rolls, E F, arranged one above the other. Two tape-rolls, E' F', are also arranged below the cylinder C, and in 70 nearly the same horizontal plane. A tape-roll, E'', is also mounted on adjustable arms supported on a suitable shaft on the main frame, and arranged slightly above the cylinder C and between it and the cutting-cylinders. 75 A similar tape-roll, F'', is mounted in similar adjustable arms a little below and in rear of the cylinder D.

At the rear of the machine, and in the upper part of the frame, is a pair of tape-rolls, E³ F³, 80 arranged one above the other, and a similar roll, F⁴, is arranged in about the same horizontal plane as the lower roll, F³, and just in rear of the two cylinders C D.

A series of carrying-tapes, *e*, pass under the 85 tape-roll E, thence over tape-roll E', under and around roll F', over the cylinder C, and back over tape-rolls E³ and E'', moving in the direction of arrows numbered 1. A second series of carrying-tapes, marked *f*, Fig. 2, passes over 90 the tape-rolls F³ F⁴ F² F in the direction of the arrow, thence over tape-roll E and under F', thence over cylinder D and between the cylinders D and C, and from that point they pass with the tapes *e* around the said cylinder 95 C and return to the roll F³.

A curved arm, G, is pivoted to the frame at the rear end of the cylinder C, and extends down over and in rear of the upper end of the blast-pipe, as shown in Fig. 6 of the drawings. Near the upper end of this arm is a curved flange, *g*, projecting inward and serving as a cam, against which the crank-arm *c³* on the end of the shaft to which the grippers *c*

are attached works when the flange-cam is thrown up. The lower end of this arm is connected by a link, g' , to an arm, h , attached to a rock-shaft, H , which is connected at one end 5 to a valve in the blast-pipe C' .

A grooved cam, G' , is fixed on the main shaft, running along the back side of the machine, and is provided with a cam-groove, g^2 , in which a pin, g^3 , on the arm G is arranged 10 to move.

It will be understood from this description that the rotation of the cam will vibrate the arm G , by which two results are effected: First, the cam g will be raised and lowered so as to 15 act at the proper time on the griper-shaft to open the gripers, while at other times it is lowered so that the crank-arm will pass over it without touching it; and, secondly, the valve in the blast-pipe will be turned to open and 20 shut off the blasts of air. These parts are so constructed, arranged, and timed that when the cam is raised to open the gripers the valve is turned to shut off the blasts entirely, and vice versa.

25 A griper-cylinder, I , and a creasing-cylinder, J , are mounted in the frame in rear of the cylinders C D and at right angles thereto, the cylinder I being provided with ordinary folding-grippers i and the cylinder J with an ordinary creaser, j . These cylinders are below the 30 tapes e f at the rear of the machine.

Above the cylinders I J is a drop-roller, K , mounted on arms in the usual way, which are attached to a rock-shaft, k , and arm k' , fastened to the rear end of this rock-shaft, extends 35 downward, and is vibrated by means of a cam, j' , on the shaft of the cylinder J . The vibration of this arm will, of course, vibrate the drop-roller, which is also provided 40 with a spring, k^2 , attached at one end to one of the arms and acting to pull the drop-roller down.

A tape-roll, K' , is mounted loosely on the rock-shaft k , and a series of tapes, L , pass 45 around the creaser-cylinder J , drop-roll K , and roller K' , and are driven in the direction indicated by the arrows in Fig. 7 of the drawings.

Just below the drop-roller are three tape-rolls, M M' M^2 , arranged as shown in Fig. 7 of the drawings, and around these rolls pass a series of tapes, m .

Two tape-rolls, N N' , are arranged inside of the griper-cylinder I , and somewhat below the 55 axis of the latter. A series of tapes, n , pass around the griper-cylinder I and the tape-rolls N N' , as shown in Fig. 7 of the drawings, and the cylinders I and J are geared so as to be driven in the direction indicated by the arrows 60 in the same figure of the drawings, thereby driving the tapes L and n in the direction of the rotation of the respective cylinders.

A reciprocating packer, O , is arranged below the tape-rolls N N' , and is operated by an 65 eccentric, O' , on the shaft of the cylinder J through the medium of a connecting-rod, o ,

rock-shaft o' , and second connecting-rod, o^2 , which extends from the rock-shaft to the packer, in a manner that will be understood without further explanation.

70

A series of fingers, P , are attached to a rock-shaft, p , just back of the packer, these fingers being bent downward and forward toward the packer, and project through recesses o^3 in the lower edge of the packer, as shown in Fig. 7 75 of the drawings.

An arm, R , is attached to the outer end of the rock-shaft p , and is actuated by a cam, r , on a stud-shaft at the rear end of the machine. This shaft also carries a gear-wheel, T , which 80 engages with a pinion, t , on the rear end of the shaft carrying the cylinder J .

The gear-wheel T and pinion t are provided with teeth having such relation to each other as to require such number of rotations of the 85 pinion to make a single revolution of the gear-wheel as may be desired, for the purposes hereinafter specified.

It is evident that the rock-shaft and fingers p will be vibrated once with each revolution 90 of the gear-wheel T ; and the rock-shaft is provided with a spring, p' , which acts to turn the fingers downward in the position shown in Fig. 7 of the drawings.

It will be understood, of course, that the several cylinders and rollers mentioned above 95 are provided with driving-gears suitably constructed, arranged, and connected with the main driving-shaft to produce the movement of the several parts, as described above and indicated by arrows in the drawings. The construction and arrangement of such gearing will be readily understood by any person skilled in the art, and does not require special description here.

105

The drawings show an arrangement of gearing which is well adapted to the purposes, though it evidently may be changed to suit different machines.

The operation of this machine is as follows: 110 The web of paper, having received its last impression from the cylinders B B' , is fed in between the cylinders B' B' , by which it is divided into sheets either by perforating or by entirely severing the web. The sheets are 115 fed in between the carrying-tapes e f , by which they are carried along over the roller E' and under the roller F' to the under side of the cylinder D . The roller E' runs at a greater speed than the cutting-cylinders, so 120 that when the sheets are perforated only they will be separated as soon as brought in contact with this roller by increasing their speed in the usual way. When the sheets reach the cylinder D they are carried up around the cylinder, underneath the tapes, and the devices are so arranged that the leading end of the sheet will meet the contact line of the cylinders C D at about the same time when the grippers on the cylinder C are brought opposite 125 to the cylinder D . Now the movement of the parts is so timed that the leading end of the

130

first sheet will reach this point when the cam g is lowered, so that the gripers on the cylinder C will not be opened. At this period of time the valve in the blast-pipe is opened, and a blast of air is consequently forced out through the branches c' and perforations c^2 down upon the leading end of the sheet, thereby causing it to be carried along upon and around the cylinder D after it passes the griper-cylinder. 5 When this end of the sheet reaches the tapes again it meets the leading end of a second sheet, and the two together are carried around the cylinder D, as above described, the second sheet imposed upon the first. When the leading ends of the two sheets are now brought to the line of contact between the cylinders C and D the air-blast will be shut off and the cam g raised to open the gripers, and the ends of the sheets are now seized by the gripers 10 and transferred to the cylinder C, being carried up around the latter between the tapes. The gripers are operated to release the ends of the sheets either when or before they reach their highest position, so that the sheets are 15 then carried along between the tapes to the rear of the machine over the folding-rollers, passing in between the drop-roller K and the tape-roller M.

The drop-roller is timed to fall upon the 20 edge of the sheet just as the leading end reaches the gage U, in front of the tape-rolls $E^3 F^3$, thereby bringing the edge of the sheet into the nip of the drop-roller and tape-roll M. The sheet will thereby be arrested and at 25 once started in another direction at right angles to its former movement, and will be carried down between the tapes L and m and delivered to the folding-cylinders I and J, where the sheet will be folded, by means of 30 the creaser and gripers, in the usual manner.

The griper-cylinder I is grooved, as shown 35 in Fig. 5, on the line of the gripers, so that the tapes n will pass below the line of the nip of the latter and permit the sheet to be creased into the griper-cylinder. The sheet is carried 40 around by the cylinder I until the gripers reach the tape-roller N' , when they are caused to release the sheet, and it is taken between the tapes n and roll N' , carried over the latter, 45 and delivered down between it and the roller N, in front of the packer.

As the fingers P are raised once with every 50 revolution of the wheel T, it is evident that at certain fixed periods one of the folded papers will be delivered in front of the packer upon the elevated fingers, thereby causing its upper edge to project above the rest of the packed papers. This operation will therefore serve 55 to count or number the papers, for it is evident that one sheet will be folded for every revolution of the pinion t , and therefore every folded paper raised by the fingers in the pack will indicate that a certain number of sheets 60 have been folded; or, in other words, every raised paper will be a tally-sheet, and the 65 number of papers between the tallies will de-

pend upon the ratio between the teeth of the wheel T and those of the pinion t —that is, if the number of teeth on the wheel is five times that of the pinion, every fifth paper will be 70 elevated in the pack; if ten times, every tenth paper, and so on.

It will thus be seen that two sheets are collected and delivered one imposed upon the other to the folding mechanism, by means of 75 which they are then folded as a single product.

It will be understood, of course, that the folding mechanism here shown and described has been used simply to illustrate the operation of the machine, and that any suitable 80 folding device may be employed constructed and arranged to produce any number of folds in the sheets which may be desired.

It will be noticed that the printing-cylinders, as represented in the drawings, are arranged 85 to make a single revolution with each revolution of the cylinders C D, and consequently the sheets collected by the latter would have the same printed matter.

It will, of course, be understood that ordinarily in printing newspapers it will be desired to impose one sheet upon another with different printed matter; and in order to accomplish this the printing-cylinders must be made twice the size here represented and run 90 at half the speed, so as to deliver two sheets of different printed matter for every two revolutions of the cylinders C D.

The machine illustrated in the drawings is adapted to collect but two sheets. It is evident, however, that by modifying the device 100 so as to shut off the air-blasts less frequently a greater number of sheets may be collected in one pack, if desired.

The air-blasts may also be introduced into 105 the cylinder D and utilized to blow the sheet from this cylinder to the cylinder C, in which case the gripers on the latter cylinder would be dispensed with; or the air-blasts may be connected with a suction device operating intermittently, so as to hold the first sheet to the cylinder D by suction, and then blow the two upon the cylinder C at the proper time to transfer them to the latter.

The air-blast pipe may also be arranged 115 outside of either of the cylinders, being, of course, located so that the blasts of air may be directed upon the ends of the sheets at the proper point or points.

Having thus described my invention, what 120 I claim as new, and desire to secure by Letters Patent, is—

1. A sheet-collecting cylinder, D, provided with tapes f , to deliver and hold the sheets thereto, in combination with the cylinder C, 125 provided with gripers c , an air-blast pipe, C' , and also with air-passages to the outer surface of said cylinder C, these said parts operating in connection with each other and with the tapes and their tape-rolls, as set forth.

2. The collecting-cylinder D, in combination with the cylinder C, provided with grip-

ers *c*, and the air-blast pipe *C'*, provided with passages leading to the outer surface of the cylinder, substantially as described.

3. The cylinder *C*, provided with transfer-ring-grippers *c*, in combination with the blast-pipe *C'*, the vibrating arm *G*, having the gripper-cam *g*, a valve in the blast-pipe connected to the arm, and mechanism for vibrating the arm at suitable periods to operate the grippers and control the air-blast, substantially as described.

4. Two sets of carrying-tapes, *e f*, in combination with the collecting-cylinder *D*, cylin-

der *C*, air-blast pipe *C'*, vibrating arm *G*, carrying the cam *g*, valve shaft or stem *H*, connected to the arm *G*, and grooved cam *G'*, substantially as described. 15

5. The carrying-tapes *e f*, in combination with the drop-roller *K*, roller *M*, tapes *L* and *m*, and folding-cylinders *I J*, substantially as 20 described.

WALTER SCOTT.
